UNITED STATES PATENT OFFICE.

MELVIN B. BENSON, OF DULUTH, MINNESOTA, ASSIGNOR OF ONE-HALF TO G. ASHLEY TOMLINSON, OF DULUTH, MINNESOTA.

RECORDING-COMPASS.

1,131,622.

Specification of Letters Patent.

Patented Mar. 9, 1915.

Application filed April 13, 1914. Serial No. 831,620.

To all whom it may concern:

Be it known that I, MELVIN B. BENSON, a citizen of the United States, residing at Duluth, in the county of St. Louis and State 5 of Minnesota, have invented a new and useful Recording-Compass, of which the following is a specification.

My invention relates to recording compasses or course-recording devices, and has 10 for its object the provision of simple, cheap and effective means for automatically recording the course or direction traveled during a given period, or at any time within such period, by a vessel, or other conveyance, or carrier whereon the device is carried and employed.

It consists of the constructions, combinations and arrangements of parts hereinafter described and claimed.

20 In the drawings, Figure 1, is a top plan view of my said invention. Fig. 2, is a side elevation thereof, partly in central vertical longitudinal section.

In the drawings, 1 is a compass bowl piv- 25 otally supported by oppositely positioned horizontal pivots 2 of any suitable construction upon a gimbal ring 3, which in turn is pivotally supported by oppositely positioned horizontal pivots (not shown) 30 to any suitable support (not shown), as in the manner well known to the art. Said bowl is covered by a glass cover 4 and preferably is approximately filled with any suitable liquid, as is usual in ships' compasses. 35 Within said bowl is a pontoon, or pontoons, 5 to which is attached a float 6. A magnetic needle 7 of any suitable construction or character is supported in said liquid by said pontoon or pontoons and float. If desired 40 an annular compass card (not shown) may be carried within said liquid by said float and pontoons. Since the parts thus far de- 45 scribed may be constructed in the usual manner of ships' compasses, well known to the art, it is not deemed necessary to describe them in further detail.

In my said invention, said float is secured to a central vertical spindle or spindles 8, by which it is secured against horizontal 50 displacement, the upper end of which spindle extends through a centrally positioned aperture or thimble 9 in said glass cover, and carries upon its upper end a horizontal card receiver 10, preferably constructed of 55 aluminum or other light non-magnetic

metal. Said card receiver is preferably provided at any suitable place or places with upwardly directed pins 11 adapted to engage notches or apertures in the herein-after described record card and to hold the 60 same against horizontal displacement with respect to its proper position plate or receiver.

12, is a record card having a series of concentric circles ruled thereon. Said circles are 65 respectively designated by numbers indicating certain hours or periods of time, or of day or night, preferably covering together a period of six hours, as either from 6 o'clock to 12 o'clock or from 12 o'clock to 6 o'clock. If 70 desired, other concentric circles may be ruled between the hour circles to represent the half and quarter hours, or other periods of time, such other circles being omitted from the drawing to avoid confusion. Outwardly 75 of said time-indicating circles, are marked upon said cards the points of the compass, and said card is so placed upon said plate or receiver that the north point thereon will correspond with the pointing of the mag- 80 netic needle when the carrier or vessel is pursuing a north course as the needle points. Intersecting said concentric circles and ex- 85 tends from the space in which said compass points are marked on said card to the center circle or to one of the inner circles thereon are a series of equally spaced lines each corresponding to the arc of a circle described by the herein-after described piv- 90 oted record arm; each of said lines terminat- 95 ing outwardly opposite to a different one of said compass points; but said lines may be of any desired number in excess of the number terminating opposite the marked points and may, without marking, represent degrees, minutes or seconds between said points.

Mounted upon said bowl in any suitable manner, as upon a bracket 13 secured thereto, is a clockwork mechanism of any suitable 100 structure, as comprising a case 14, a main spring 15, a main wheel, 16, a pinion 17 driven by said main wheel, a sleeve 18 driven by said pinion 17, a pinion 19 and gear 20 driven by said sleeve, a gear wheel 105 21 driven by said pinion 19, an arbor 22 driven by said gear 21, a pinion 23 driven by said arbor 22, a gear wheel 24 driven by said pinion 23, an arbor 25 driven by said gear wheel 24, a pinion 26 driven by said arbor 110

25, a gear wheel 27 also driven by said pinion 23, an arbor 28 driven by said gear 27, an escapement wheel 29 driven by said arbor 28, a fork 30 engaging said escapement wheel at one end, and at its opposite end engaging a pin 31 upon a balance wheel 32, which balance wheel is governed by a balance spring 33. But such clock mechanism may be of any suitable construction, 10 and I do not desire to be understood as limiting my said invention to the employment of the particular clock mechanism shown or described.

Pivottally secured in any suitable manner 15 to said case is a horizontal record arm 34 extending outwardly over said record card and adapted to swing over such portion of said card as from time to time may be presented beneath it, according to the oscillation or rotation of the compass needle on its 20 axis. Upon the outer end of said record arm is mounted a tracing instrument of any suitable structure or character, as a fountain pen 35 adapted in operation to mark or 25 chart upon said card the actual compass course pursued by the vessel or carrier whereon said compass is carried and used. Upon the opposite end of said record arm is formed or secured a segmental rack 36 30 adapted to mesh with said pinion 26, whereby said record arm is swung upon its pivot, and the outer end caused to move across said card, either from the outer circle toward the inner circle, or vice versa, as predetermined. 35 Beneath said record arm is preferably positioned a cam 37 adapted to lift and lower said record arm so that the marking pen will be brought into contact and lifted out of contact with the record card at regular 40 intervals. Said cam is mounted on a cam shaft 38 which is provided at its opposite end with a pinion 39 adapted to mesh with said gear 20, whereby it is rotated. But said cam, cam shaft, pinion 39 and gear 45 wheel 20 may be omitted if desired.

Upon the record card, Fig. 1, is shown in broken lines a hypothetical course as if traced by the marking pen, indicating that the carrier started on a northeasterly course 50 and pursued such course for about a half an hour, and then swung rapidly to a north-northwesterly course and pursued such course for about an hour, and then swung

rapidly to a westerly course and pursued such course for about an hour, and then 55 swung rapidly to a north-northeasterly course and pursued such course for about twenty minutes, and then turned slowly to a northerly course where the record terminates under the pen point. The course 60 as so described is approximate only, since the index circles and radial or tangential curves and time marks and compass points on the record card indicated are, to avoid confusion, few in number; but in practice, 65 the course and time consumed in swinging from one course to another, or in following any course may be very accurately determined.

In the drawings the clock mechanism and 70 counterbalance $\mathbb{X}$ are obviously disproportionate to the size of the compass shown, and to avoid confusion teeth or cogs have not been shown on any of the pinions and 75 gears, but in practice all these minor inaccuracies would be corrected in the manner well known to the art, and I do not desire to be understood as restricting myself to the particular clock-mechanism, or to the proportions of the parts shown. 80

The construction may be modified or altered in details within the spirit and scope of my claim.

What I claim is—

In a recording compass, the combination 85 with a compass bowl or chamber, of a spindle mounted therein and adapted to rotate or oscillate in opposite directions, a magnetic needle carried by said spindle for rotating or oscillating the same, a removable 90 sheet adapted to receive a record and supported by said spindle and adapted to rotate or oscillate therewith, a recording arm extending over a portion of said chamber and provided with means for marking said 95 sheet, said arm being pivoted at a point beyond the periphery of said sheet to a support carried by said bowl, and means supported by said bowl for swinging said recording arm upon its pivot. 100

In testimony whereof I hereunto affix my signature, in presence of two witnesses.

MELVIN B. BENSON.
